UNITED STATES PATENT OFFICE

AUGUSTUS J. PENOTE, OF CLEVELAND, OHIO.

SECTIONAL FORM.

Application filed November 7, 1924. Serial No. 748,377.

This invention relates to forms used in construction work, especially in man-hole construction of concrete or other suitable cement material which is to be molded about 5 the form, ordinarily external of the latter.

These forms are usually rectangular and used to make man-holes of that outline, and my present invention is a further improvement on my prior Patent No. 1,316,462, 10 issued to me Sept. 16, 1919. It is also like that structure in that this form is to be built in sections so that the latter may be readily withdrawn from the interior of the man-hole after the latter has been formed 15 and even after the cement has set. All advantages claimed for my earlier construction as disclosed in said patent are gained in the present improved structure now to be described.

20 My patented form sections contemplated the use of wood for structural material, but this has proven to have certain inherent disadvantages, such as the gradual decay when used in damp locations, and warping of the 25 parts, as well as gradual enlargement of apertures in use and a far larger space required for storage. I have found that thin sheet metal is much more satisfactory for general use, but that a modified structure 30 for the sections used is desirable—arrangement of which was not contemplated when the said patent was issued. By my new and improved forms I have been able to dispense with the oblique-angled members before employed, and yet the readiness of assembling 35 and manufacturing has been even accentuated.

With these and other objects in view which will be explained hereinafter, my invention 40 consists in the described structure set forth in the appended claims and illustrated in the accompanying drawings, in which—

45 Figure 1 is a perspective view with a corner broken away, of a man-hole form of three courses embodying my invention;

Figure 2 is a top plan view of one end of the form;

50 Figure 3 is a horizontal section of one corner of the form, the remainder of one end of the form being shown in plan;

55 Figure 4 is a detail view of a horizontal joint between courses including vertical joints between certain plates of the same courses, and

Figure 5 is a vertical section taken on the line 5—5 of Fig. 3.

My new and improved form may be built or constructed in a plurality of courses of uniform size and character designed to be superposed when assembled for operation, and the form here illustrated is represented as comprising three such courses designated by letters A, B and C, respectively. Each of these courses is made up of rectangular plates four in number designated by numeral 10, and each comprising a thin metal plate having flanges on each of its four sides all inclined at right angles to the main plate. Ordinarily the side flanges 11 are integral with the plate and bent up from the same, and designed to be positioned at the upper and lower edges of the plate in a vertical man-hole. The end flanges are however separate pieces formed as L's or angle bars 12 either riveted or spot-welded to the edge of the main plate, as shown clearly in Fig. 3. These bars are also rather thin, ordinarily about $\frac{1}{8}$ inch in thickness, as are also the main plates themselves. 80 These plates 10 are used for the central side plates of the courses as well as the end plates, but not for the corner plates, as will be further explained hereinafter.

The corner sections or plates 13 each 85 comprises a smooth main plate 13^a and a shorter plate 13^b integral therewith but at right angles thereto to form a corner section. The end flanges on these pieces 13^b are also angle bars 12 secured to the edges 90 of the plates 13, while the upper and lower, or side flanges are angular in plan view and integral with the main plates. These are designated in the drawings as 14. These end bars 12 on the short plates 13^b of the 95 corner sections 13 will therefore be substantially parallel with the flanges or bars 12 of the central sections 10. They will not however, be strictly parallel, for these bars or L's 12 are never exactly 90° in cross section. This is a well-known fact as to all L bars which are supposed to be approximately a 90° angle—they are all at least 40° less than 90°, and this fact is made use of by applicant in designing a structure 100 which can be readily disassembled by removing the several sections inwardly. This feature will be further explained in the description of operation hereinafter.

The side plates 14 or top and bottom 110

flanges of the corner sections, 13, are formed of two parts, the longer flange 14^a being integral with the plate 13^a, and the shorter flange 14^b integral with plate 13^b. Before 5 the plate 13^b is bent into its final shape, a V-notch is cut from the sheet from which the plate 13 is to be fashioned, so that when the main plate is bent, the plates 14^a and 14^b are also bent inward and their oblique 10 edges 15 meet as shown clearly in Figs. 2 and 3. A plate 16 is then applied immediately beneath the ends of said plates bridging the meeting edges 15, and is spot-welded thereto, as shown in said views. 15 This plate 16 is of proper size to avoid possible interference with the wedging plates later to be described.

Between the several sections of a course, metal plates 17 are inserted so that the removal of the same will so loosen the adjacent sections that the latter may be removed inwardly dismantling the entire form. 20 These plates are smooth and thin—usually approximately $\frac{1}{8}$ inch in thickness, there being a separate divider plate for each joint of each course. Such plates are used not only between the corner and intermediate sections at the sides of the form, but also between the corner and end sections at each 25 end of the form. In assembling the form, the flanges 12 of the adjoining sections and the divider plates 17 are provided with apertures 18 registering when the form is set up, and bolts 19 are used for securing the three 30 parts together as shown in Figs. 1, 3 and 4. These bolts have slots 19^a therein slightly remote from the end and wedge plates 20 are inserted in said slots to tighten the flanges 12 and divider plates 17 in position. 35

40 Cross braces 21 are also provided for strengthening the form when set up, the same comprising metal L-bars which are in two or more sections, which latter are in engagement, face to face, and corresponding 45 flanges of each section have spaced apertures in which locking bolts 22 are secured to hold the sections together, the braces being thus adjustable in length by applying the bolts in the proper apertures chosen 50 from a larger number than are needed, as shown in Figs. 2 and 3.

55 At the ends of each section, the one flange of the L is folded over the other flange, as at 23, as shown in Figs. 1, 2 and 3, to provide flat surfaces parallel with one of the flanges, there being apertures 24 in said flat end portions to receive therein the same bolts 19 which secure together the divider plates and frame sections, so that the same 60 securing means serves to hold the plate sections together as well as brace the entire structure.

65 To hold the several courses of my structure in superposed position, apertures 25 are provided in the flanges 11 of the plates 10

which are designed to receive locking pins 26 to lock flanges of adjacent plates 10, the apertures in the different flanges registering when in proper position. These pins may be readily removed when it is desired to dismantle the structure. 70

A very advantageous feature of my structure is made use of to provide metal hollow sockets in the concrete wall that is molded about this form structure. Bolts 31 are inserted in apertures 29 of certain plates of the form, the bolts being directed outward with the bolt heads on the inner surface of the plates and the threaded end projecting on the outside. A metallic socket which 80 is to be embedded in the cement wall exterior of the form plates consists of a reduced hollow threaded portion 27 which is provided with inner threads of the proper size to receive the threaded ends of the said bolts, 85 and a larger hollow portion 28 having an outer closed end, the two parts 27 and 28 being integral and 28 being intended to be secured in the cement wall with its larger end preventing accidental removal. It is 90 evident that if a number of said fixtures be supported by the form externally thereof while cement is being molded about the same, the sockets 27 and 28 will be securely fastened in the cement casing when the cement sets, and will be permanently fixed 95 in the desired position.

For expedited handling of the plates 17, apertures 30 are provided near their inner edge, as shown in Figs. 4 and 5. These enable the plates to be placed either into position between the form plates, or to be pulled from such position with quite a strong force when the form is to be dismantled. 100

105 In operation, the first or lower course is laid in the earth cavity provided for the purpose by positioning the side and end sections 10 independently with the proper corner sections 13 between, as shown in Fig. 1. Divider plates 17 are then forced into 110 position at all the joints between sections of the course. Then, if braces 21 are to be used, the sections thereof are adjusted by securing therein the bolts 22 in the proper apertures to result in the desired length of 115 braces, and the latter are held in position with the apertures 24 of the braces in register with the apertures 18 of the sections and dividers, so that the bolts 19 may be inserted and the wedges 20 forced into the 120 slots 19^a to hold the entire structure in engagement. Sometimes assembled courses may be lowered into position. The other courses are then laid in superposed position with the apertures 25 in registration for the 125 reception of the pins 26, thus holding the courses together. As many courses may be used as needed to attain the required height of the completed form, and a covering is provided by laying cross pieces over the 130

top of the material most convenient for the purpose, an opening being provided therein of the desired size and shape for permitting entrance to the man-hole or such structure 5 which is formed of concrete or other cementitious material.

In dismantling the structure (the form), the bolts 31 are unscrewed from the sockets leaving the latter fixed in the hardened cement casing, thus providing internally-threaded sockets in the surface of the casing, a great advantage, since it is difficult to bore sockets in the cement walls after the latter is set, the wedges 20 removed and the 10 bolts 19 withdrawn from the braces and flanges, thus releasing the divider plates 17 so that by engaging the apertures 30 the plates 17 may be readily removed inwardly, it some times being practicable to insert a 15 hand tool in said apertures, such as a hook or a rod, to facilitate the removal. In any case, the fact that the angle of the angle bars 12 is slightly less than 90° makes the removal and insertion of the plates 17 an easy 20 operation. After the removal of those plates, the disengagement of the other parts or sections will evidently be easily accomplished since no appreciable friction is present to oppose the operation. When the parts are 25 separated, they may be readily withdrawn upward through the entrance opening for storage or for transportation to another place where needed.

It is to be understood that the terms 30 "sides", "ends", "upper" and "lower" are used for convenience in description, and are not intended to be considered as strictly structural limitations, as the completed form 35 may be positioned in any desired relation to the surface of the ground where used, with equal facility.

It is evident that the structure disclosed 40 may be used without the braces if so desired, and such use is contemplated. Further, 45 while the sections used for the form require only the plates 10 and corner plates 13, used with the dividers 17, it is obvious that these 50 may be made of different sizes, or filler side or end plates may be used, being exactly like the plates 10 except that the width might be 55 less or greater than the standard plates. When more than one side or end plate 10 is used in a course, an additional divided 17 is also used, and in the same way as when but 60 one plate 10 is used. This has the advantage therefore that the filler plates need not be of a different pattern from the standard plates—only a possible variation in their width.

65 From the above disclosure it is evident that I have invented a composite form that is wholly of metal and which may be used for molding a casing externally thereof, thus meeting the requirements for a positive and rigid structure of relatively thin material

combined with great strength, requiring small storage space and light in weight; that has no oblique angles in its entire extent; and which notwithstanding these advantages, permits certainty of manipulation in assemblage and is likely to result in little variance in shape from wear of material in long use thereof. 70

It is evident that changes may be made in details of my construction, and I desire 75 to cover in the appended claims all modifications that fall well within the spirit and scope of the disclosed invention.

What I desire to secure by Letters Patent and claim is,— 80

1. A rectangular form for concrete construction work comprising four counterpart corner sections and four counterpart intermediate sections, each intermediate section comprising a flat plate, upper and lower 85 members and end members which are at an angle to said flat plate, each corner section comprising a relatively long plate, a relatively short plate making a right angle with the first named, top and bottom members and two end members which are inclined with respect to the long and the short plates of the corner section, the said end members of adjacent intermediate and corner sections being slightly out of parallel with each other, 90 the inner edges of the respective end members being spaced slightly more than the edges of the respective flat plates and flat divider plates separating the said end members of the intermediate and corner sections 95 and engaging them contiguously. 100

2. A rectangular form for concrete construction work comprising four counterpart corner sections and four counterpart intermediate sections, each intermediate section comprising a flat plate, upper and lower flange members and end members which are at substantially right angles to said flat plate, each corner section comprising a relatively long plate, a relatively short plate making a right angle with the first named, top and bottom members which make right angles with the long and short plates of the corner section and two end members which are inclined to and make acute angles at least 110 twenty seconds less than right angles with the long and short plates of the corner section, flat divider plates separating the said end members of the intermediate and corner sections and engaging them contiguously, 115 and detachable securing means for binding together the said end members of adjacent sections and the dividing plates therebetween. 120

3. A rectangular form for concrete construction work comprising four counterpart corner sections and four counterpart intermediate sections, each intermediate section comprising a flat plate, end members which are inclined to and make acute angles slight- 125 130

- ly less than right angles with said flat plate, each corner section comprising a relatively long plate, a relatively short plate making a right angle with the first named and end members which are inclined to and makes angles slightly less than right angles with the long and short plates of the corner section, and flat divider plates separating the said end members of the intermediate and corner sections and engaging them contiguously with tighter binding action at the outer edges of the divider plates than at the inner contact edge.
4. A rectangular form for concrete construction work comprising four counterpart corner sections and four counterpart intermediate sections, each intermediate section comprising a flat plate, end members which are inclined to and make acute angles slightly less than right angles with said plate, each corner section comprising a relatively long plate, a relatively short plate making a right angle with the first named and end members which are inclined to and make angles slightly less than right angles with the long and short plates of the corner section, the angle between said end members of adjacent sections when the latter are in contiguity being less than one degree, and flat divider plates having parallel faces separating said end members, whereby the binding force at the outer edges of the divider plates is greater than at the contact areas at the inner edges of the end members.
5. A rectangular form for construction work comprising counterpart corner sections and counterpart intermediate sections, each intermediate section comprising a flat plate and end members which are at substantially right angles to said flat plate, there being apertures in said end members, each corner section comprising a relatively long plate, a relatively short plate making a right angle with the first named and apertured end members which are at substantially right angles to the long and short plates of the corner section, flat divider plates separating the said end members of the intermediate and corner sections and having apertures therein registering with the apertures in said end members when the parts are in engagement in substantial parallelism, brace members adjustable as to length and provided with apertures near their ends, and detachable bolt members inserted through the apertures in the end members, divider plates and braces, to lock the parts together.
6. A rectangular form for concrete con-

struction work comprising counterpart corner sections and counterpart intermediate sections, each intermediate section comprising a flat plate upper and lower flanges integral with said plate and end members which are at substantially right angles to said flat plate, each corner section comprising a relatively long plate, a relatively short plate making a right angle with the first named, top and bottom flange members and two end members which are inclined with respect to, and make substantially right angles with the short and long plates of the corner section, flat divider plates separating the said end members of the intermediate and corner sections and engaging them face to face contiguously, the top and bottom flange members of the sections forming supports and engaging portions for superposed courses of forms above specified, said flanges being provided with openings adapted to receive fastening devices.

7. In a form for molding concrete construction, a rectangular section comprising a flat plate, upper and lower flange members integral with said plate and bent at right angles thereto and end flange members comprising L-members one of whose angle plates is fixedly secured to a face of said flat plate adjacent an edge at an end of the latter and the other angle plate of said L-member extends from said flat plate at an angle to said flat plate slightly less than 90°, the said end flange members of adjacent sections being slightly more separated at their inner edges than at their outer edges.

8. In a form for molding concrete construction, a plurality of metal sections each comprising a flat plate having attached L-members one of whose plates is fixed to a face of said flat plate adjacent an edge and the other angle plate of said L-member extends from said flat plate at an angle thereto, flat divider plates separating the L-members of adjacent sections, the angle which the several extended angle plates makes with the flat plate, and the thickness of the divider plates being such that the pinching effect of the extended angle plates upon the divider plate will be slightly greater at the outer edge of the divider plate than at its inner edge, whereby the said divider plates may be the more readily inserted or withdrawn from between the said L-members.

In testimony whereof I hereunto affix my signature.

AUGUSTUS J. PENOTE.
